UNITED STATES PATENT OFFICE.

CHARLES C. DRUEDING, OF PHILADELPHIA, PENNSYLVANIA.

DESIGN FOR A WATCH-BAG.

SPECIFICATION forming part of Design No. 35,591, dated January 21, 1902.

Application filed May 14, 1901. Serial No. 60,244. Term of patent 14 years.

To all whom it may concern:

Be it known that I, CHARLES C. DRUEDING, a citizen of the United States of America, residing in the city and county of Philadelphia, in the State of Pennsylvania, have invented and produced a new and original Design for Watch-Bags, of which the following is a specification, reference being had to the accompanying drawings, forming part thereof.

Figure 1 is a side elevation of a watch-bag, showing my new design. Fig. 2 is a plan thereof. Fig. 3 is a vertical section of the same.

My design consists in the form or configuration of a watch-bag. It is composed of two sides and is flat in planular outline, as usual.

Its distinguishing and novel features are the slightly-contracted neck-like portion *aa* near the open mouth or top of the bag and the flaring mouth portion *bb*, the latter proceeding from and being a continuation of the upper curved part of the neck.

I claim—

The design for a watch-bag, substantially as herein shown and described.

In testimony whereof I have hereunto affixed my signature in the presence of two subscribing witnesses.

CHARLES C. DRUEDING.
